HYDRAULIC FUEL INJECTOR

John D. Fague, Philadelphia, Pa.

Application April 20, 1939, Serial No. 269,031

3 Claims. (Cl. 123—139)

My invention relates to fuel injectors for internal combustion engines.

An important object of my invention is the provision of a fuel injector for an internal combustion engine that will thoroughly atomize and preheat the fuel before combustion.

Another object of my invention is the provision of a fuel injector for an internal combustion engine that will substantially increase the efficiency of the engine, and that will effect a more thorough burning of the fuel.

Yet another object of my invention is the provision of a fuel injector for an internal combustion engine that may be easily attached to any of the standard makes of engines.

Still another object of my invention is the provision of a fuel injector for an internal combustion engine that is efficient in operation, simple in construction and inexpensive to manufacture.

Other objects and advantages of my invention will be apparent during the course of the following description.

In the drawing, forming a part of this specification, and in which like numerals are employed to designate like parts throughout the same,

Figure 1 is a vertical sectional view of a device embodying my invention, and showing the same associated with an internal combustion engine,

Figure 2 is a transverse sectional view taken on the line 2—2 of Figure 1, and

Figure 3 is a transverse sectional view taken on the line 3—3 of Figure 1.

In the accompanying drawing, wherein for the purpose of illustration is shown a preferred embodiment of my invention, the numeral 10 designates the engine block of an internal combustion engine having cylinder walls 11 positioned therein and pistons 12 reciprocally mounted within said cylinder walls. The piston 12 is provided with the conventional piston rings 13 to permit the same to have a close frictional engagement with the inner peripheral wall of the cylinder.

My device embodies a cylinder head 14 fitted to the block 10 in vertical abutting relation with the cylinder walls 11 and having a vertically disposed housing 15 integrally formed therewith and disposed centrally above each of the pistons 12.

It is to be understood that while the fuel injector is here illustrated as being associated with but one of the pistons that each piston of the motor is provided with a similar device incorporated into the cylinder head directly thereabove, and that while the description will be re-

stricted to but one of the fuel injectors, each is of an identical construction and functions in the same manner to produce the same result.

The lower face of the cylinder head 14 is provided with an annular recess 16 which is adapted to register with the inner face of the cylinder walls 11. A vertical bore 17 is formed in one end of the housing 15 and in alignment with the longitudinal center of the piston 12. The housing 15 is substantially elliptical in cross section and a bore 18 is formed therein and spaced laterally from the bore 17 by a transverse wall 19. The bore 17 comprises a pressure cylinder and the lower end 20 thereof constitutes a high pressure precombustion chamber which is in direct communication with the cylinder 11 and the top of the piston 12. The chamber 20 is formed at substantially its point of communication with the cylinder 11 with an annular shoulder 21 and a substantially cup-shaped opening 22 of slightly smaller diameter than the cylinder 17 which opens directly onto the center of piston 12. The bore 18 comprises an injector cylinder the lower portion of which terminates in a substantially conical seat 23 which includes a laterally extending passage 24 communicating therewith and with the side wall of the pressure cylinder 17 a substantial distance above the shoulder 21. The transverse closure wall 19 is provided with an opening 25 which affords communication between the bores 17 and 18 adjacent their top. The cap screw 27 is threadedly received in an opening 26 at the top of the pressure cylinder 17 and may be removed when it is found desirable to gain access to the said cylinder.

The built-up piston 29 is slidably mounted within the cylinder 17 and is formed with a plurality of piston rings 30 interposed between the sections to assure a close frictional engagement thereof with the peripheral face of the cylinder. The bottom face of the piston 29 comprises a plate 31 formed with an upwardly extending shank 32 the end of which is threaded to receive the pal-nuts 33. The nuts 33 may be rotated longitudinally along the shank 32 to properly tension the laminated sections of the pistons and to regulate the cohesive attraction of the piston with the cylinder walls. The expansion spring 34 is interposed between the top of the piston and the cap screw 27, and the lower end 35 thereof receives the upwardly extending end of the shank 32 and the upper end 36 thereof receives the downwardly extending shank 28 of the cap screw 27. The spring 34 functions to normally position the piston 29 within the pre-

combustion chamber 20 and with the plate 31 in engagement with the shoulder 21. The housing 15 is formed with a threaded opening 37 in the top portion thereof adjacent the threaded opening 26 and the said opening 37 is of a slightly larger diameter than the cylinder 18 to form an annular shoulder 38.

A built-up piston 39 is slidably mounted within the cylinder 18 and is formed with a plurality of laminated sections 40 having piston rings 41 interposed therebetween to assure a close frictional engagement thereof with the inner face of the cylinder wall. The sections 40 are similarly provided with a bottom plate 42 of substantially conical formation to permit the same to properly seat within the conical recess 23 of the cylinder and having an upwardly extending shank 43 the upper end of which is threaded to receive pal-nuts 44. The retractile spring 45 is interposed between the top of the piston 39 and a packing gland 46 which is threaded into the opening 37 of the housing 15. The lower portion of the spring 45 is formed with a plate-like element 47 having a central opening adapted to receive the shank 43 and to be held in interlocking engagement between the top of the piston 40 and the lower pal-nut 44. The upper end of the spring 45 is formed with substantially plate-like structure 48 having an outwardly extending annular flange 49 adapted to be received within the lower portion of the opening 37 and in abutting relation with the shoulder 38. The packing gland 46 is threaded into the opening 37 and abuts the upper surface of the plate-like element 48 to hold the same securely wedged therein. The packing gland 46 is formed with central longitudinal bore 50 and upwardly extending shank 51 which receives the packing nut 52 to securely hold the inner end of the feed line 53 of the hydraulic fluid tank (not shown). The feed line 53 is in direct communication with the bore 50 and the spring actuated check valve 54 is positioned in the lower portion of the bore 50 to permit hydraulic fluid from within the fluid tank to enter within the cylinders 17 and 18. The retractile spring 45 functions to normally hold the piston 40 retracted within the cylinder 18 and with the plate 42 positioned a substantial distance above its seat 23.

The laterally extending bore 55 communicates with the side wall of the cylinder 18 in a substantially constricted opening 56 at a point slightly below the normal position of the lower end of the piston 40. A mixing valve 57 is positioned within the bore 55 and securely held therein by means of the stud bolts 58. The mixing valve 57 is formed with a longitudinally extending bore 59 which communicates with the outlet port 56, and an air inlet tube 60 is integrally connected to the valve and in communication with the outer end of the bore 59. The sleeve 61 is integrally formed with the valve 57 and positioned within the passage 59 in annular spaced relation with the wall thereof. The sleeve 61 terminates adjacent the port 56 and in communication therewith. The fuel feed inlet pipe 62 communicates with the interior passage of the sleeve 61 at a point diametrically opposed to the air inlet passage 60, and a needle valve 63 extends through the packing nut 64 and packing gland 65 to terminate at the outlet end of the sleeve 61. The needle valve 63 may be governor-actuated or hand-actuated at the discretion of the user and is adapted to be actuated longitudinally of the mixing valve to substantially regu-

late the mixing ratio of the fuel from the fuel line 62 with the air from the air inlet pipe 60.

The head 14 is formed with an annular internal recess 66 which encircles but does not communicate with the lower portion of the pressure cylinder 17 and the injector cylinder 18, and the said recess may be filled with water, or the like, to impart a cooling effect to the cylinders.

The operation of my device is as follows:

A cylinder head constructed in accordance with the present invention may be attached to a four-cycle or a two-cycle engine with equally efficacious results. A hydraulic liquid is forced into the cylinders 17 and 18 above their respective pistons 29 and 40, and this hydraulic fluid may be used to lubricate the pistons and to assure the operation thereof in an efficient and efficacious manner. The spring actuated valve 54, positioned at the point of communication of the inlet pipe from the hydraulic fluid tank with the cylinder, controls the inflow of the said fluid and permits a quantity to flow into the cylinders necessary to maintain the same in a filled condition. As illustrated in Figure 1, the valve 54 seats outwardly of the packing gland 46 in a manner to prevent the fluid from backing into the fluid inlet pipe 53 upon actuation of the pistons 29 and 40.

Assume that the cylinder head 14 is attached to the engine block of a two-cycle engine and that the power piston 12 has completed a power stroke and has uncovered the exhaust port to permit the escape of the gases and vapors within the upper portion of the cylinder 11. The exhaust pressure in the cylinder will now be only slightly above the atmospheric pressure depending upon the pressure of the fluid resistance through exhaust valves, piping, mufflers, etc. The reduced pressure in the cylinder will permit the expansion spring 34 to force the piston 29 into the precombustion chamber 20 and seated on the shoulder 21 to close the fuel inlet passage 24. As the piston 29 moves downwardly in the chamber 17 under the resilient action of the expansion spring 34 there will be a displacement of the hydraulic fluid within the cylinders and the injector piston 40 will be permitted to move upwardly simultaneously therewith under the resilient action of the retractile spring 45 a sufficient distance to uncover the fuel inlet port 56. When the needle valve 63 has been properly regulated, the requisite mixture of fuel and air will be impinged through the port 56 and into the lower portion of the injector cylinder 18. Due to the constricted proportions of the outlet port 56 a thorough mixing of the air and fuel will be assured as it is forced under pressure therethrough. At this time the piston 29 is seated on the shoulder 21 to prevent the escape of the fuel within the injector cylinder 18. When the power piston 12 begins the compression stroke it will close the exhaust port and cause the air inlet port to be uncovered, so that a charge of heated air will be injected through the said inlet port, pushing out the remaining burned gases, and leaving a fresh charge in the cylinder 11. As the power piston moves upwardly in the cylinder 11 it will exert a pressure on the bottom face of the piston 29 through the substantially large opening 22 sufficient to force the piston upwardly within the pressure cylinder 17 and against the action of the expansion spring 34. The upward actuation of the piston 29 will uncover the fuel passage 24 and cause a displacement of the hydraulic fluid thereabove to be effected. The displacement of the fluid will cause a force to be

exerted on the upper face of the piston 40 sufficient to simultaneously move the same downwardly in the cylinder 18 against the resilient action of the retractile spring 45 to close the fuel inlet port 56 and to seat the plate 42 in the conical recess 23. As the piston 40 moves downwardly to obturate the fuel inlet port 56, the quantity of fuel vapor in the lower part of the cylinder 18 will be forced through the fuel passage and into the precombustion chamber 20 of the cylinder 17 where it will be mixed with the fresh charge of heated air in the power cylinder 11. The actuation of the pistons 29 and 40 will not be effected to inject the fuel from the cylinder 18 into the precombustion chamber 20 until the power piston 12 approaches the top dead center on the compression stroke, and as the fuel is forced through the constricted passage 24 it will be thoroughly agitated to cause final combustion in the chamber 20 and to drive the power piston downwardly in the cylinder 11 on its power stroke. The combustion force created in the power cylinder will hold the pressure piston 29 in the elevated position and the added impetus imparted thereto by the final combustion will be transmitted through the hydraulic fluid to the upper face of the injector piston 40. The said force imparted to the injector piston by the combustion of the fuel in the chamber 20 will insure a tight seated condition thereof with the seat 23 to force all of the fuel therein through the passage 24 and into the combustion chamber 20. As illustrated in Figure 1, it will be noted that the area of the pressure piston is substantially greater than that of the injector piston so that the force acting on the pressure piston from the power cylinder is greater at all times than that acting on the injector piston. As the power piston 12 completes the power stroke, the exhaust port will be uncovered to permit the escape of gases and the cycle of operation will then be repeated as hereinbefore described.

The operation of the device hereinbefore described, when used in association with a four-cycle engine, would be substantially the same. The pressure and injector pistons in the head 14 will be maintained in the combustion position, illustrated in Figure 1, while the power piston is making the power and exhaust stroke. When the power cylinder is making the suction and compression strokes, the pistons 29 and 40 will be forced to the injecting position under the resilient action of their respective coacting springs to permit a fresh charge of fuel to be injected into the precombustion chamber 20 for ignition upon the approach of the power piston to the top dead center on the compression stroke.

It may thus be seen that the operation of the injector pistons will be automatic in their action and that the fuel supply may be regulated and determined in the same manner as for a two-cycle engine. By placing the fuel inlet port 56 in direct communication with the injector cylinder 18, the formation of air pockets between the mixing valve and the injector will be substantially eliminated, and by causing the suction created within the lower portion of the cylinder 18 upon the upstroke of the piston 40 to draw the fuel charge into the cylinder, the use of mechanically operated valves have been eliminated and the force created by the power piston on its compression stroke will be positively hydraulically transmitted to the injector piston to assure the complete expulsion of the

fuel from the injector cylinder to the precombustion chamber.

It is to be understood that the form of the invention, herewith shown and described, is to be taken as a preferred example of the same, and that various changes in the size, shape and arrangement of parts may be resorted to without departing from the spirit of my invention. or the scope of the appended claims.

- 10 Having thus described my invention, I claim:
1. In an internal combustion engine including cylinders and power pistons reciprocally mounted therein; the combination of a cylinder head covering the cylinders of the said engine and having a pair of spaced vertical bores positioned above each of the said cylinders, one of said bores constituting a pressure cylinder, the lower portion of which comprises a precombustion chamber which has a substantially unobstructed communication with the related cylinders, the other of the said bores constituting an injector cylinder which freely communicates with the said pressure cylinder adjacent its top and having a constricted discharge passage 15 communicating with the pressure cylinder adjacent its bottom; a pressure piston mounted for reciprocation within said pressure cylinder; an expansion spring interposed between the pressure piston and the top of the said cylinder 20 to hold the said piston normally positioned in the precombustion chamber of the said cylinder and to close the said discharge passage; an injector piston mounted to reciprocate within said injector cylinder; a tension spring connected to 25 the top of the said injector bore and to the said injector piston to hold the said piston normally retracted from the bottom of the cylinder and above the said discharge passage; and a fuel mixing valve communicating with the said injector cylinder below the normal retracted position of the said injector piston.

2. An injector comprising a casing having spaced parallel bores of unequal diameters, one end of the larger bore opening exteriorly of the casing, one end of the smaller bore having an essentially unrestricted communication with the larger bore at the end thereof remote from the outlet end and an essentially constricted communication with the larger bore adjacent its outlet end; a fuel supply means communicating with the smaller bore adjacent the last-mentioned end; pistons slideable in the bores, the larger piston being normally positioned to close the last-mentioned end of the smaller bore, and the smaller piston being normally positioned to permit a charge of fuel to be introduced therein; and means to supply a hydraulic fluid above the pistons, whereby movement of the larger piston away from its outlet end and in a direction to open the last-mentioned end of the smaller bore will effect displacement of the hydraulic fluid to move the smaller piston into obturating relation with the fuel supply and to force the fuel charge therein into the larger bore.

3. An injector comprising a casing having spaced parallel bores constituting pressure and injector cylinders, respectively, said pressure cylinder opening exteriorly of the casing at one end and with the other end thereof in unrestricted communication with the injector cylinder, said injector cylinder being formed at one end with a valve seat having a restricted communication with the pressure cylinder adjacent its outlet end; means to introduce a charge of

fuel into the injector cylinder adjacent the said valve seat; pressure and injector piston valves slidably mounted within said cylinders, said pressure valve being normally positioned to close the last-mentioned end of the injector cylinder and the said injector valve being normally positioned away from its seat to permit a charge of fuel to be introduced into the injector cylinder, the portion of the cylinders above the piston valves being filled with a suitable hydraulic fluid, whereby movement of the pressure valve in a direction to open the last-mentioned

end of the injector cylinder will effect a displacement of the hydraulic fluid to drive the injector valve against its seat to impinge the charge of fuel into the pressure cylinder, and
5 wherein combustion of the fuel in the pressure cylinder will cause the pressure valve to act upon the injector valve through the medium of the hydraulic fluid to drive the said injector valve into pressed engagement with its seat to assure
10 a complete expulsion to the said fuel charge.

JOHN D. FAGUE.
